United States Patent Office

Des. 188,191
Patented June 14, 1960

188,191

TURNSTILE

Carlile R. Stevens, 7045 Trolleyway, Playa Del Rey,
Calif., and Norman F. Stevens, Rte. 1, Box 608, Ramona, Calif.

Filed Jan. 8, 1960, Ser. No. 58,963

Term of patent 14 years

(Cl. D28—1)

Figure 1 is a front perspective view of a turnstile embodying our new design;

Figure 2 is a top plan view thereof;

Figure 3 is a left side elevational view thereof; and

Figure 4 is a rear elevational view thereof.

The dominant features of our design for a turnstile reside in the portions shown in full lines.

We claim:

The ornamental design for a turnstile, substantially as shown and described.
